ATTORNEY.

UNITED STATES PATENT OFFICE

JOHN WILLIAM WATERER, OF GREENWICH, LONDON, ENGLAND, ASSIGNOR TO BAR-
ROW, HEPBURN & GALE, LIMITED, OF LONDON, ENGLAND

HANDLE

Application filed June 25, 1927, Serial No. 201,389, and in Great Britain March 23, 1927.

A compact stowage of the handles of portable and other articles and for other purposes when the handles are not in use, is desirable with many different types of handles, 5 as for example those on portable gramophones, cameras, and the like which now up- stand rather pronouncedly and in many cases inconveniently, from the surface of the case, inconvenience stepping in on account of 10 obstruction, as for instance, if a winding handle or other working part has to be inserted at or near or adjacent to the handle, or, if a fall down front is laid upon a table or other support, or if a number of cases of 15 gradually increasing size are desired to be nested for space economy in transit, or to enable a travelling trunk to be stood squarely upon its ends upon which a handle is normally fitted or to enable a box or case to be 20 neatly stored in a confined space, as, for example, the removable cases of a motor trunk.

According to the present invention there is 25 provided a compact stowing handle for portable articles and other purposes having a longitudinally flexible handle capable of being arched or of lying flat, or substantially so, and provided with slide guides on or secured to the article lying in a plane parallel, or substantially parallel, to the article, in 30 which each end of the handle is attached to one end of a link forming a longitudinal extension of the handle, the other end of which link slides freely in the corresponding slide guide to allow the handle ends to move away 35 from the surface and towards each other during the arching, and move towards the surface and recede from each other during the flattening.

Arching the handle is preferred to be 40 opposed by yielding means which re-act positively on the sliding connection with the article so that the handle when not in use is automatically returned to and retained in its alternative and normal position lying flat or 45 flush on the article.

The drawings show a constructional example of the invention, Fig. 1 being a side view of an attaché case, Fig. 2 a section on 50 1—1 of Fig. 1, Fig. 3 a plan view, Fig. 4 a section on 3—3 of Fig. 3, Fig. 5 an enlarged sec-

tion on 1—1 of Fig. 1, Fig. 6 is a plan view of a recessed handle, Fig. 7 a section on 6—6 of Fig. 6, and Fig. 8 an end view of one of the handle plates.

In the drawings, 1 is a strip or blade of 55 spring steel embodied in a leather handle 2 and having links 3 at its ends.

The links 3 move in hollow fittings or handle plates 4, 5 on the article, the links 3 not being wider or substantially wider than the 60 width of the handle and being able to recede into the hollow fittings or handle plates 4, 5 in a notably elegant manner.

The hollow fittings or handle plates 4, 5 are in the form of shallow box-like plates 65 having a pair of slots or notches 6, 7 in the end wall opposite the handle ends for the purpose of receiving the links 3 in sliding engagement therewith.

These shallow box-like plates may be secured to the article in divers ways. One way which serves well is to provide the plates with tangs or ears 8 adapted to be passed through the wall of the article and folded or doubled back toward or away from each 75 other to lie along the inside of the wall (Fig. 4) to which if desired they may be further secured.

It is preferred as shewn that the clothing of leather or other material of the handle 80 does not take the load as this is taken by the steel strip or blade 1 with its integral sliding links 3, the handle really being a metal handle but resembling a handle of leather or some equivalent material, the spring strip 1 being energized by arching the handle and re-acting positively on the sliding connection with the article to self-return the handle to a 85 flat position.

In use the handle 2 arches under the load 90 and the links 3 slide into contact with the nearer sides of the box-like fittings 4, 5 on the article and pivot to allow movement of the handle ends away from the surface, but on the removal of the load following the release of the hand-grip, the action of the spring 1, positively returns the handle 2 to its normal position lying against the surface of the article 9, or flush in a recess 10 therein, 95 and the links 3 which are end-on or in tandem 100

with or in the plane of the handle 2 when this is not in use are positively caused to recede into the hollow handle plates 4, 5.

In the flush forms of the present invention 5 lateral recesses 11 may be provided for facilitating access to the handle.

The handle recess in any article may be provided in any suitable or approved way, for example, by removal of material, by 10 forming, or by building up, or otherwise.

In a modified form of the invention one end 15 of the handle may be fixed and the whole movement of approach and recession for arching or opening of the handle given to the other end.

The present invention rather notably lends 20 itself to mass production under favourable conditions with regard to manufacturing assembling and fitting economies.

25 The effect of the blade spring 1 may just as well be obtained by cylindric spiral tension springs 12 (Fig. 3) attached to the links, or the links may pull against cylindric spiral compression springs, the springs in either 30 case reacting positively on the links to self-return the handle to a flat position. No claim is made to springs attached to the handle ends per se.

The bulk of the handle may be increased 35 for heavier articles without opposing the action of the spring, by using as a longitudinal packing a strip of rubber 13 which may serviceably be of semi-torpedo shape. 14 is a fibre strip packing.

40 The term "parallel" used in the claims is to be read as meaning "parallel or substantially parallel".

What I claim is:—

45 1. A collapsible luggage handle, comprising a longitudinally flexible handle portion capable of being arched and flattened, links connected to the opposite ends of the handle portion and providing longitudinal extensions thereof, and slide-guides adapted for 50 attachment to the luggage in position to receive said links, said links being curved lengthwise and adapted to slide freely in said guides and in a plane substantially parallel with the surface of the luggage.

55 2. A collapsible handle for luggage, comprising a handle portion longitudinally flexible and adapted to be arched and flattened, links mounted upon the opposite ends of the handle portion and providing longitudinal 60 extensions thereof, and a relatively flat enclosed housing arranged at each end of the handle portion and adapted to receive said links therein, said links being curved lengthwise of the handle portion and adapted to freely slide into and out of said housings in a plane substantially parallel with the surface of the luggage.

65 3. A collapsible handle for luggage comprising a longitudinally flexible handle portion capable of being arched and flattened, a

spring in said handle portion for normally urging the same into flattened position against the side of the luggage, a link mounted upon each end of the handle portion, a slide guide of box formation mounted on the luggage at each end of the handle portion for receiving said links, said links being curved longitudinally to admit of the free sliding movement of the links in said guide and in a plane parallel with the surface of the luggage.

In testimony whereof, I affix my signature.
JOHN WILLIAM WATERER.
